UNITED STATES PATENT OFFICE.

PAUL ARBON, OF TULSA, OKLAHOMA.

METHOD OF MAKING DRILLING JARS.

Application filed March 17, 1924. Serial No. 699,938.

The present invention relates to the production of drilling jars and resides particularly in assembling such jar sections in such a manner as to eliminate any possible weakened points in the assembled construction.

The object of this invention is to provide a drilling jar which will be cheap and convenient to manufacture but which will at the same time be of such construction that the stress and strain on the parts will be properly accommodated and in which the liability of breakage is negligible, it being obvious to one skilled in the art that the rupture of an element of the present invention during a drilling operation will be expensive both in time and labor and might result in the total destruction of a well.

Other objects whereby the necessary "rope action" is obtained and the undesirable features of drilling jars now on the market are entirely eliminated will appear by reference to the accompanying specification and drawings.

Reference will be had to the accompanying drawings forming a part of this specification, and wherein like characters of reference designate corresponding parts throughout the several views, in which

Fig. 1 is a side elevation of the completed assembled socket;

Fig. 2 is a vertical section through Fig. 1;

Fig. 3 is a side elevation illustrating the manner of inserting the T-head into the socket according to the first method mentioned;

Fig. 4 is a vertical section through the socket shown in Fig. 3;

Fig. 5 is a sectional view on line 5—5 of Fig. 1;

Fig. 6 is a sectional view on line 6—6 of Fig. 2;

Figs. 7, 8, 9 and 10 illustrate the various steps in assembling a drilling jar such as is shown in Fig. 1, according to the third method described.

Before describing the various steps and methods involved in the production of this jar, attention is directed to Figs. 1 and 2 for the purpose of obtaining familiarity with the finished product. In these figures, the body A will be seen to include the lateral opening B through which the swiveled head C is inserted, the latter carrying the cable D. The guard pin b extends parallel to the axis of the body and prevents the escape of the swivel. Lower transverse per-

forations a are arranged for the reception of the conventional pin to prevent the escape of the swivel to the longitudinal passage.

The body A is elongated for the application of the present T-head connection, and the lower portion of the body has extending therethrough a continuation of the longitudinal passage formed in the upper portion for the reception of a swivel. This passage, however, is slightly enlarged from the lower walls of the transverse pin perforations, downwardly as indicated by reference character E. Two oppositely arranged lateral passages extend through the wall at F and F' for a considerable portion of their length for the reception of the lateral extension forming the T-head of the lower section, as will more clearly hereinafter appear.

The lower member G includes the body and the upper annular shank. This upper shank includes the flattened head portions formed by the lateral extensions g, g' and the vertical extensions g'', the entire head being in the form of a cross. The arms or extensions g, g', are constructed to fit and travel within the passages F, F', extending outwardly and terminating flush with the outer face of the body portion A. The upper extension corresponds to the dimension of the enlarged portion of the longitudinal passage to permit the movement of the same therein during the upper movement of the head, it being apparent that the lateral extensions g, g', at the end of their upper stroke engage the walls f, f'. The upper annular shank is of sufficient diameter to permit proper clearance during movement within the longitudinal passage.

In Figs. 3 and 4, the first method of assembling this jar is illustrated. In Fig. 3, it will be seen that the lower end of the body is cut at H for a distance to equal the length of the enlarged longitudinal passage, or for such a distance as may be necessary to procure the proper expansion of the cut end to permit the introduction of the head of the lower section. This cut is made by any suitable means such as a saw, and the leg portions 8 and 8' are expanded until the heads can be inserted. These legs 8 and 8' can then be brought together by a hammer or other suitable mechanism, and welded.

The second method for making the jar is illustrated in Figs. 7, 8, 9 and 10. Both sections of the filling jar are forged and

machined with the exception of the finishing of the pins. As illustrated, the socket section includes a slot of sufficient dimensions to insert the T-head. This slot includes the necessary lateral passages at a distance spaced from the lower end and as shown in Fig. 10, this portion between the lower terminals of the lateral slots and the ends of the jar sections includes the enlarged portions L. A finished T-head is inserted in the slot and is moved to its upper position to permit engagement at M with the upper wall of the slot. Inserts N are placed in position between the lower faces of the T-head projection and the upper edges of the enlarged portions L, L. Before inserting the T-head, the lower part of the socket section of the jar is heated and after the T-head is inserted and these inserts N, N are placed in position, those enlarged portions L, L are hammered into the slots Q around the neck of the T-head. The heated portion is allowed to cool and the shrinkage due to the cooling produces the necessary working clearance. Should it be found that the stroke is insufficient, portions of the shoulder R may be machined off. During the finishing operation, the movable parts may be clamped or wedged into a fixed position.

30 What I claim as new and useful and desire to secure by Letters Patent is:—

1. A method of making drilling jars consisting in forming a socket member with oppositely disposed slots, forming a stem member with a T-head having substantially flat sides, heating one of said members and inserting the stem member in the socket mem-

ber so that the cross bar of the T-head will extend into said slots, and then shaping the heated member to cause the socket member to surround the stem member and prevent the T-head from pulling out of said slots. 40

2. The method of forming a drilling jar, consisting in forming a flat T-head section of the jar and maintaining the same in a cold state, forming a socket member with opposite longitudinal slots and with an opening of sufficient diameter to permit the insertion of the T-head, heating a portion of the socket member, inserting the T-head section into said socket and the ends of the cross bar of the T-head into said slots, and shaping the heated portion of said socket member to cause the same to surround the stem of the T-head section. 55

3. The method of forming a drilling jar, consisting in making a stem member with a T-shaped head and maintaining the T-head in cold condition, forming a socket member with oppositely disposed longitudinal slots of greater length than either end of the cross head of the T, providing the outer end of the socket member with an endless wall, then inserting the T-head through said endless wall and permitting the ends of the cross bar of the T-head to extend into said slots, heating said endless wall, placing inserts into the slots between the T-head and the endless wall, and then contracting the endless wall to cause the same to surround the stem of the T-head and to prevent the T-head from being pulled out of the slots. 60 70

In testimony whereof I affix my signature.

PAUL ARBON.
